UNITED STATES PATENT OFFICE.

DAVID S. GARCIA, OF OAKLAND, CALIFORNIA.

CONDENSATION TRAP.

Application filed August 10, 1927. Serial No. 211,963.

This invention relates to condensation ejector traps of the type disclosed in a prior patent issued to me August 17, 1926 bearing #1,596,172 entitled Condensation ejector trap.

It is the principal object of the present invention to generally improve the construction and operation of devices of the character referred to whereby to provide an efficient condensation ejector trap capable of continuous operation to drain any amount of condensation rapidly from equipment at any temperature or pressure, and assisting rather than retarding the circulation of the steam, resulting in more heat efficiency and no loss of live steam; the device being designed with no wearing parts, and capable of adjustment to give any desired capacity.

One form which the invention may assume is exemplified in the following description and illustrated by way of example in the accompanying drawings, in which:

Fig. 1 is a side elevation of a device embodying the preferred form of my invention.

Fig. 2 is a longitudinal section through the device disclosing its construction.

Referring more particularly to the accompanying drawings I have disclosed therein a condensation ejector which may be inserted in the exhaust steam line for the removal of condensation from steam processing or heating equipment.

As illustrated the device comprises a cylindrical shell 10 having a removable inlet head 11 at one end and a removable outlet head 12 at its opposite end. As here shown each head is shouldered and provided with an exteriorly threaded cylindrical portion of reduced diameter adapted to threadedly connect the head to the end of the shell 10.

The interior of the shell is divided into four chambers by means of partition walls 14, 15 and 16. The chambers in which the shell is divided are a receiving chamber 17, a spray chamber 18, liquefaction chamber 19 and an ejector chamber 20. It will be noticed that the receiving chamber 17 is at the receiving end of the shell while the ejector chamber 20 is at the outlet end of the shell. Communication is established between the two through the medium of intermediate devices hereinafter described, so that the vapor and condensate will pass through the inlet head 11 through the device. For this purpose the inlet and outlet heads 11 and 12 are provided with ports 21 and 22 which are

tapped so that the device may be interposed in the exhaust steam line of any desired apparatus.

Arranged within the receiving chamber 17 is a pipe 23 which is arranged at right angles to the axis of the shell. At its lower end this pipe 23 is fitted with a strainer 24 which is threaded into a port 25 in the partition wall 14. This port 25 is located contiguous to the outer circumference of the partition 14 as illustrated. At the other or upper end of the pipe 23 it is fitted with a non-clogging strainer 26. The position of this strainer 26 makes it necessary that the receiving chamber 17 be almost full of water at all times; thus providing a water seal over the inlet port 21 of the shell. This chamber 17 also acts as a sediment chamber as any sediment passing into the shell through the port 21 cannot pass through the screen or strainer 26 and will collect at the bottom of the chamber 17. This sediment may be removed from time to time through the plugged drain opening 27.

Steam and condensate entering the receiving chamber 17 passes through the strainer 26 downwardly through the pipe 23 and enters a similar pipe 28 arranged in the spray chamber 18. This pipe 28 is also arranged at right angles to the longitudinal axis of the shell and its lower end is placed in communication with the pipe 23 of the receiving chamber 17 through the medium of an elbow 29. The other or upper end of the pipe 28 extends to a point almost on the level with the strainer 26 and is fitted with a conical spray nozzle 30. Hence, steam and condensate passing through the strainer 26 and pipe 23 will pass into the pipe 28 and discharge into the chamber 18 through the spray nozzle 30.

The spraying action taking place causes the steam and water to again mix freely. Consequently the force of the spray causes the water to evaporate rapidly. This evaporation of the condensate is accompanied by the disappearance of a large quantity of heat and frequently by a diminution of temperature, which brings a change of sensible into latent heat, and of kinetic into potential energy again causing the vapor and condensate to temporarily displace in chamber 18.

A given amount of water in aeroform condition occupies nearly 1700 times as much space under a pressure of one atmosphere as it does in liquid form. That is, one

cubic foot of steam when condensed will yield approximately one cubic inch of water. For this reason these displacements take place very rapidly in chamber 18, thus retarding the inflow from chamber 17 until the water and vapor discharge into chamber 19.

To accomplish this at its lower end the partition wall 15 is offset slightly so that it may communicate with a pipe 31 arranged in the liquefaction chamber 19. That is, the chamber 18 communicates with the interior of the pipe 31 through the latter's lower end which is threaded through the partition 15. The upper end of this pipe is plugged as illustrated. Contiguous to its upper end however, the pipe 31 is formed with an orifice 32 communicating with the interior of the pipe. This orifice faces the partition 16 so that the mass passing from chamber 18 into chamber 19 through the pipe 31 in an aeroform condition will impinge on the partition 16 and pass into the liquid state again, which operation is assisted by the further diminution of heat in the chamber 19.

Reference being had to the drawings, it will be seen that the partition wall 16 is formed similar to that of 15 so as to establish communication between the chamber 19 and an ejector pipe 33. This ejector pipe is arranged in chamber 20 and it communicates with the chamber 19 at its lower end. The upper end of the pipe 33 is closed. An orifice 34 is formed in this pipe contiguous to its upper end so that the fluid passing from chamber 19 into the pipe 33 will discharge through the orifice 34 as illustrated.

A sleeve valve 35 is arranged over the upper end of the pipe 33 to control the orifice 34. This valve 35 is provided with a stem 36 extending outwardly through the wall of the shell. In fact the stem 36 is threaded through the wall of the shell so that rotary movement given to the stem will move the valve 35 coaxially of the pipe 33 to cover and uncover the orifice 34. For regulating the position of the valve 35, the outer end of the stem 36 is fitted with a hand wheel 37 so that the effective area of the orifice 34 may be changed to suit conditions. I prefer to term the pipe 33 an ejector nozzle.

It is obvious from this foregoing that the orifice 34 in the ejector nozzle may be regulated to suit conditions. This adjustment is necessary only at the time of installation of the device to meet the most extreme operating conditions. Once the proper adjustment is made no further attention is required and thus the ejector can be made to handle from the smallest to the largest amount of condensation by simply regulating the valve 35.

In operation of the device it is assembled in an exhaust steam line as described. If the ejector is operated at pressures equal to

or greater than atmospheric at the inlet side, it will be filled with water throughout its chambers and at the same time the water will be flowing through the different chambers at varied velocities. This is chiefly owing to the friction of the liquid particles against the sides of the pipes. It will be noted from the drawings that there is a higher water seal in chamber 18 and a lower water seal in chamber 20 due to the position of the orifice on the ejector nozzle 33.

If steam is present in chamber 17 there will be a slight leakage of steam through the spray nozzle in chamber 18 providing there is no condensation present in the pipe line, but due to the fact that the volume of a pound of steam is very large and the orifice of the spray nozzle 18 is small in area, and as the radiation of heat from the top of the ejector against which the nozzle sprays is such as to aid in condensing the steam rapidly, then the rate of given amount of steam flowing through the area of the orifice will be less than the rate of condensation of the steam, and any steam which tends to pass through the orifice 32 in chamber 19 with only a pound per square inch difference of pressure between each chamber would be condensed into water as it entered chamber 20 through the ejector nozzle.

It is obvious from the foregoing description and from the drawings that there are no moving or wearing parts in the device and that none of the parts require packing; thus insuring that the device will serve at maximum efficiency for a considerable period of time. It should also be apparent that the device is continuous in operation and will act to drain any amount of condensation quickly from equipment while giving more heat efficiency and without the possibility of becoming flooded.

Due to the adjustable features of the structure it can be adjusted expeditiously to give any desired capacity.

While I have shown the preferred form of my invention, it is to be understood that various changes may be made in its construction by those skilled in the art without departing from the spirit of the invention, as defined in the appended claims.

Having thus described my invention, what I claim and desire to secure by Letters Patent is:

1. A condensation ejector trap comprising a shell having an inlet port at one end and an outlet port at its other end, said shell being interiorly partitioned to provide a receiving chamber in communication with the inlet port and an ejector chamber in communication with the outlet port, fluid conveying means for conveying fluid from the receiving chamber, said conveying means receiving fluid from a point above the inlet port whereby the receiving chamber will be par-

tially filled with water to form a steam seal, an ejector nozzle arranged within the ejector chamber through which fluid passes into the ejector chamber, and valve means for controlling the discharge of fluid through the ejector nozzle.

2. A condensation ejector trap comprising a shell having an inlet port at one end and an outlet port at the opposite end, said shell being interiorly partitioned to provide a receiving chamber and an ejector chamber, a conduit arranged in the receiving chamber for conveying fluid from the receiving chamber, one end of said conduit being open and fitted with a strainer and disposed above the inlet port whereby a water seal will be provided in the receiving chamber, the other end of said conduit being closed in the receiving chamber and directing the fluid through said partition, an ejector nozzle arranged in the ejector chamber to convey fluid into the ejector chamber, and valve means for controlling the discharge of fluid through said ejector nozzle into the ejector chamber.

3. A condensation ejector trap comprising a shell having an inlet port at one end and an outlet port at the other end, said shell being interiorly partitioned to provide a receiving chamber, a spray chamber and an ejector chamber, a strainer arranged in the receiving chamber and disposed above the inlet port, a spray nozzle arranged in the spray chamber on substantially the same plane as the strainer, fluid conducting means connecting the strainer with the spray nozzle, the position of said strainer and spray nozzle causing a fluid level in the receiving chamber and spray chamber sufficient to maintain a steam seal, said spray nozzle being restricted whereby to retard the flow of the fluid through the spray chamber, an ejector nozzle in the ejector chamber through which fluid passes into the ejector chamber from the previous chambers, and valve means controlling the discharge of fluid through said ejector nozzle.

4. A condensation ejector trap comprising a shell having an inlet port at one end and an outlet port at its opposite end, said shell being interiorly divided into a receiving chamber, a spray chamber, a liquefaction chamber and an ejector chamber, a strainer in the receiving chamber above the inlet port, a spray nozzle in the spray chamber on the plane of the strainer, conduit connecting the strainer with the spray nozzle, said conduit extending below the inlet port and through the partition dividing the receiving chamber

from the spray chamber, a tube in the liquefaction chamber communicating at its lower end with the spray chamber contiguous to the bottom of the spray chamber, an orifice in the side of said tube above the center of the liquefaction chamber and directed toward the succeeding partition, a tube in the ejector chamber communicating at its lower end with the bottom of the liquefaction chamber, said tube having an orifice therein substantially in alignment with the outlet port, and valve means for controlling the effective area of said orifice.

5. A condensation ejector trap comprising a cylindrical shell having removable head members at opposite ends, the head member at one end being formed with an inlet port, the head member at the other end being formed with an outlet port, said ports being arranged on the axis of the shell, said shell being interiorly divided by partitions into a receiving chamber, a spray chamber, a liquefaction chamber and an ejector chamber, the receiving chamber being contiguous to the inlet port and the ejector chamber contiguous to the outlet port, a strainer within the upper end of the receiving chamber, a conduit arranged at right angles to the axis of the shell and connected with the receiving chamber at one end, the other end being directed through the adjacent partition, a conduit in the spray chamber arranged in parallelism with the conduit in the receiving chamber, the lower ends of said conduit being connected, the upper end of the conduit in the spray chamber being fitted with a restricted spray nozzle, a conduit in the liquefaction chamber arranged at right angles to the axis of the shell and communicating at its lower end with the lower end of the spray chamber, the upper end of the conduit in the liquefaction chamber being closed, said conduit in the liquefaction chamber being formed with an orifice in its side directed toward the succeeding partition and being disposed above the center of the shell, a conduit in the ejector chamber arranged at right angles to the axis of the shell and communicating at its lower end with the lower end of the liquefaction chamber, said conduit in the ejector chamber being formed with an orifice substantially on the axis of the shell and directed toward the outlet port, a valve controlling said orifice, and means exteriorly of the shell for operating said valve to control the effective area of said orifice.
